DISK BIT

Application filed December 15, 1926. Serial No. 154,887.

This invention relates to the rotary system of drilling wells and particularly to disk bits.

In the well producing industry it is common practice to drill wells by the rotary system in which a rotary bit is secured to the lower end of a drill pipe, the drill pipe being rotated by means of a rotary table mounted in a derrick of the well. The drill bit operates on the bottom of the hole and thus deepens it. In the ordinary form of disk bit

the disk cutters are attached to a body. One of the features of the disk bit is that it has extensive cutting edges and will therefore

outwear the ordinary fish-tail bit. This is true if the disks rotate so that the entire cutting edges of the disks are employed. In order for the disks to rotate it is necessary that they be placed a distance away from the axis of rotation so that the force applied thereto while cutting will cause them to rotate. If the disks are thus arranged a space is provided between them and the central part of the bottom of the hole is not cut away.

This causes a core to form which extends up, engaging the lower end of the body of the bit, thus impeding drilling or deflecting the bit to one side, which results in the drilling of a crooked hole. If the disks are placed near the axis of rotation, the core will be prevented from forming but the disks will not rotate. It is ordinary practice to compromise the positions of the disks, placing them between the two extreme positions so that there will be but a small core formed and a slight amount of rotation.

It is an object of this invention to provide a disk bit having a disk near the axis of rotation which will rotate. I accomplish this object of the invention by providing a bit having outer and inner disks which are connected together. The outer disk which is rotated by the action on the bottom and walls of the hole causes the inner disk to rotate.

It is accordingly one of the objects of this invention to provide a disk bit in which an outer boring and reaming disk cutter rotates an inner bottoming disk cutter near the axis of rotation.

The ordinary form of disk bit cannot be

made in small sizes because the parts can not be made strong enough to endure the enormous strains placed upon them while in the well. One weakness of the ordinary disk bit results from the placing of the disks on separate supporting pins. In my invention I provide what I call spool cutters which consist of integral shafts and cutters. It is possible to make disk bits according to my invention much smaller than can be done with the ordinary bit.

It is accordingly an object of this invention to provide a disk bit which is very rugged, even in smaller sizes of bits.

In order to properly support the spool cutter of my invention so that it may rotate, it is necessary to provide a split support having a portion on each member of the support which extends partly around the hub of the spool cutter, the two portions cooperating to provide a bearing. The support members are in turn secured together by a body.

It is an object of this invention to provide a novel form of disk bit having spool cutters which may be conveniently assembled.

It is an object of the invention to provide a disk bit having split support members which are held together in a novel manner.

It is a still further object of the invention to provide a disk bit having extensible cutters.

Other objects and advantages of the invention will be made evident hereinafter.

Referring to the drawings in which I illustrate the invention,

Fig. 1 is a diagrammatic view illustrating the utility of the invention.

Figs. 14, 15 and 16 are diagrammatic views illustrating the principle of operation of the spool cutters.

Fig. 17 is a vertical section through another form of the invention.

Fig. 18 is a section taken on the line 18—18 of Fig. 17.

Fig. 19 is a section taken on the line 19—19 of Fig. 17.

Referring to the drawings in detail and particularly to Fig. 1, 25 is a partly drilled well which is being drilled by means of a rotary disk bit 26 embodying the features 25 of this invention. The rotary disk bit 26 is attached to the lower end of a drill pipe 27 which extends upward through the well 25 to a point above the surface of the ground. At the surface of the ground is a derrick 28, 30 carrying a traveling block 29, by means of which the drill pipe 27 is partly supported. The traveling block 29 is connected to a swivel head 30 which is secured to the upper end of the drill pipe. The floor of the derrick supports a rotary machine 31, by means of which the drill pipe is rotated. Rotary mud is supplied under pressure to the bit 26 by means of a high pressure pump 33 which is connected to the swivel head 30 by means of a stand pipe 34 and a flexible hose 35. The mud is forced downward through the drill pipe 27 to the bit 26. The purpose of the rotary mud is to carry the cuttings of the bit to the surface of the ground and to prevent 45 cave-ins. The details of the bit 26 are shown in Figs. 2 to 13 inclusive.

The bit 26 has a body 36 which is provided with threads 37 at the upper end thereof, by means of which it may be attached to a collar 39 (Fig. 1) of the drill pipe 27. The lower part of the body 36 is provided with a cylindrical socket 40 which is open at the lower end of the body. Extended into the socket 40 is an insert 41 of a cutter support 42. The 55 cutter support 42 is provided in two parts, consisting of two cutter support members 43 such as shown in perspective in Fig. 13. The insert 41 which rests in the socket 40 is composed of a pair of semi-inserts 44.

60 The insert is retained in the socket 40 by means of a retainer 45. The retainer 45 has a lower head 46 which rests in a cavity 47 formed in the cutter support members. The cavity 47 is connected to the upper end of the 65 insert 41 by means of an opening 48 through

which a neck 49 of the retainer 45 extends. A threaded portion 50 of the retainer 45 is screwed into a socket 51 of the body 36, and a tubular body 53 of the retainer 45 extends upward through a central opening 54 of the body 36, terminating slightly below the upper end thereof. The retainer 45 holds a shoulder 55 of the cutter support 42 in engagement with a lower face 56 of the body. The cutter support 42 is prevented from rotating relative to the body 36 by means of lock lugs 57 formed on each of the cutter support members 43, which lock lugs 57 rest in recesses 58 provided at the lower end of the body 36. The retainer 45 is screwed into the position shown in the drawings so that the cutter support 42 is retained in the position shown by means of a key (not shown) which fits into slots 59 formed in the upper end of the tubular portion 53. After the retainer 45 has been screwed into the position shown, it is retained in this position by means of a lock member 61. The lock member 61 consists of a body 62 which is extended into the upper end of the opening 54. The lock member 61 is restrained from rotation by means of splines 63 which extend into vertical grooves 64 formed in the upper end of the body 36 and connect to the upper end of the opening 54. The lower end of the lock member 61 is provided with tongues 66 which connect to the lower end of the body 62, these tongues 66 extending into the slots 59.

The cutter support 42 has a collar portion 68 formed below the insert 41. Extended downward from the collar portion 68 are spaced legs 69. A part 70 of each leg 69 is formed on each cutter support member 43. Supported by the legs 69 are spool cutters 73 which are shown clearly in Figs. 8, 9 and 10. Hubs or bearings 74 of the spool cutters 73 extend through bearing openings 75 provided by the legs 69. The bearing openings 75 are formed by cooperation of two semi-bearing openings 76 formed in cooperating parts 70 of the legs 69. Formed integrally at each end of the hubs 73 are inner bottoming disk cutters 77 and outer boring and reaming disk cutters 78. Surrounding the hubs or bearings 73 are wear plates 79 which are adapted to protect the bearing openings 75 from being worn to a larger size. The wear plates 79 are composed of sections 80 (Fig. 12) having semi-cylindrical portions 81 and radial flange portions 82. The semi-cylindrical portions 81 project through the bearing openings 75 and the flange portions 82 rest between the inner faces of the legs 69 and outer faces of the inner cutters 77.

As is evident from the drawings the spool cutters 73 must be placed in the position shown in the drawings at the time the cutter support members are assembled. Referring to Fig. 8, the spool cutters 73 are offset equal distances on opposite sides of a center line

A—A of the bit, which center line A—A extends through the axis of rotation. Offset the disks in this manner is common in the art.

5 Rotary mud is supplied to the disks of the bit through the drill pipe 27. The rotary mud passes through an opening 85 in the lock member 61 and through an opening 86 formed through the retainer 45. As shown 10 best in Figs. 2 and 13, the cutter support 42 is provided with a main rotary mud passage 88 which connects to the bottom of the collar 68. Joined to the main passage 88 are branch passages 89 which are extended diagonally outward, opening to the bottom of the collar 68 at the outside of the legs 69. If desired, the passages 88 and 89 may be lined 15 with tubes 90 and 91 for preventing a leakage of rotary mud between contacting flat 20 faces 93 of the cutter support members 43.

In assembling the bit just described, the sections 80 of the wear plates 79 are placed in the semi-bearing opening 76. If the tubes 90 and 91 are used, they may at this time be 25 placed in the semipassages 88 and 89 of this cutter supporting member 43. The head 46 and neck 49 of the retainer 45 are then placed in the semi-cavity 47 and the semi-opening 48. After this assembly, the other cutter 30 support member 43 is placed against this first cutter support member 43 in its proper position as illustrated in Fig. 2 of the drawings. The parts are held in this position and the insert 41 provided by the cooperation of 35 the insert portions 44 is extended into the cavity 40 of the body 36. The upper end of the threaded portion 50 engages the threaded socket 51 of the body 36. The key (not shown) is then inserted into the 40 upper end of the opening 54 of the body 36 so that the retainer 45 may be rotated. The retainer is screwed into the position shown and the cutter support 42 is drawn upward in the socket 40 until the lock lugs 57 rest in 45 the recesses 58 and an annular shoulder 55 engages the lower face 56 of the body 36. The lock member 61 is then placed, as shown in Figs. 2, 3 and 4, so that the retainer cannot unscrew. This completes the assembly 50 of the bit.

The operation of the bit is substantially as follows.

The drill pipe 27 is rotated by the rotary table 31 and rotation is thus imparted to the 55 bit. The inner cutters 77 engage the bottom of the well and the outer cutters 78 bore and ream the walls of the well and, as pointed out in the preamble, if the disks are placed near the axis of rotation they ordinarily will not 60 rotate. This may be readily explained by reference to Fig. 16. In Fig. 16 which is extremely diagrammatic, the line B—B represents an axis of rotation. 98 is a disk cutter which is placed on the axis of rotation B—B. 65 When the disk cutter is rotated in a direc-

tion indicated by the arrow 99 of Fig. 16, a force is exerted against the right edge thereof as indicated by the arrow 100. There is no force tending to rotate the disk 98 by reason of the fact that it is on the axis of rotation B—B. Dotted lines 102 represent a disk which is removed from the axis of rotation B—B and is moved around it on a radius represented at C. When the disk represented by dotted lines 102 is moved around the axis of rotation as indicated by the arrow 99, there will be a force against the right edge, as indicated by the arrow 103, this force being similar to the force against the disk 98 as indicated by the arrow 100. There will also be a force against the lower right-hand portion of the disk 102 in a direction indicated by the arrow 104. The force having the direction of the arrow 104 tends to rotate and in actual practice will rotate the disk 102 on its own axis of rotation, which is indicated by the line D—D. Fig. 16 clearly illustrates why the disk will rotate when it is placed at a position away from the axis of rotation and why it will not rotate when it is placed on the axis of rotation.

Fig. 15 shows disks 105 which are placed away from the axis of rotation so that they will rotate properly. It will be noted however that there is a large space between these 95 disks which permits a relatively large core to be formed. The formation of a core will interfere with the proper operation of the bit. Dotted lines 106 in Fig. 15 represent disks placed close together so that no core 100 will be formed, but when the disks are in this position they will not rotate on their own axes and therefore only practically a quarter of their cutting edges will be utilized. They will therefore last no longer than an 105 ordinary disk bit.

Fig. 14 is a diagrammatic view illustrating the disks of my invention. The outer disks 78 travel along a circumferential path 109 and the inner disks 77 travel along a circumferential path 110. The rotating tendency of the outer disks 78 is considerable because they are placed quite a distance from the axis of rotation E in Fig. 14; therefore, as the bit is rotated the outer disks 78 will rotate on their own axes as well as travel along the path 109. The inner disks 77 are attached to the outer disks 78, being integral therewith; therefore, the rotating tendency of the outer disks 78 causes the inner disks 77 to rotate. The inherent tendency of the inner disks 77 to rotate by their engagement with the bottom of the hole is practically nil and there is a force exerted against the working part of the cutting edges such as the one indicated by 115 the arrow 100 in Fig. 16 which works against the rotation of the inner cutter. This force will therefore slow down the rotation of the cutter spools 73. The cutter spools rotate faster than they would if they were rotated 120

by the inner cutter 77 but slower than they would rotate if they were rotated by the outer cutter 78 without the resistance of the inner cutter 77. The operation of both of the spool cutters is the same.

5 This feature of the invention is very important since it makes it possible to provide bottoming cutters near the axis of rotation so that no core may be formed, which cutters 10 are caused to rotate so that their entire cutting edges will be utilized. Another advantage of rotating the disks is that a slicing action is effected, this being quite an advantage over the ordinary fish-tail bits and disk bits in which the disks do not rotate, but have merely a scraping action.

Referring to Fig. 9 in particular, it will be seen that the length of the hubs or bearings 73 is greater than the width of the legs 69, there being a space 112. The cutter spools are therefore free to move along their own axes from positions shown by dotted lines 113 of Fig. 9 or by full lines in Fig. 8 into positions shown by full lines in Fig. 9. 25 This constitutes the extendible feature of the bit. When the bit is lowered into the well, generally through a casing, the spool cutters 73 are placed in retracted positions as shown in full lines in Fig. 9. When they reach the 30 bottom of the well and the bit is rotated, the engagement of the inner and outer disks 77 and 78 causes the spools 73 to move into proper operating position as shown by dotted lines 113 in Fig. 9 and as shown by full lines in 35 Fig. 8.

In Fig. 11 I show an alternative form of spool cutter. Referring to this figure, the spool cutter consists of an inner bottoming member 116 and a boring and reaming member 117. The inner member 116 consists of a disk 118 and a threaded pin 119. The outer member 117 consists of a disk 120 and a hub 121 having a threaded opening 122 formed therethrough into which the threaded pin 40 119 is screwed. A lock washer 124 is placed between the end of the hub 121 and a shoulder 125 provided by the inner member 116. As 45 the parts are screwed together, as shown in Fig. 11, they may be welded as indicated at 126. I desire however to make the spool cutters integral, since an integral structure is much stronger. In larger sizes of disk bits they may be made in two parts, as shown in Fig. 11, but in smaller disk bits where 50 great strength must be had it cannot be had if the parts are not made integral. I prefer to make the spool cutters in the form shown in Fig. 10.

Another form of the invention which is 55 shown in Figs. 17 to 19 inclusive, consists of a cutter support 130 which is formed from cutter support members 131 which are equivalent to the cutter support members 36 of the first form of the invention. These members 131 and faces 132, when they are proper-

ly assembled, engage each other. The cutter support provides an insert 133 in the form of a threaded pin which is screwed into a socket 134 which is provided with complementary threads. The socket 134 is formed in a body 135. The body 135 is provided with threads 137 by means of which it may be attached to a collar 138 secured to the lower end of a drill pipe.

Formed below the insert 133 is a collar 140 having an upper annular shoulder 141 which engages a lower face 142 of the body 135. The circumference of the collar 140 is provided with flutes 143 so that a wrench used in screwing the insert into the body 135 may obtain a tight grip. Extended from the collar 130 is a pair of spaced legs 145. The legs 145, as in the case of the first form of the invention, are formed from leg portions 146 provided by each cutter support member 131. The leg portions 146 cooperate to provide a bearing opening 147 in which wear plates 148 are placed. Bearings or hubs 150 of cutter spools 151 similar to the cutter spools 73 extend through the wear plates 148. The cutter spools have inner cutters 153 and outer cutters 154. Formed through the cutter support 130 at the engaging faces 132 of the cutter support members 131 is a main rotary mud passage 156. Connected to the main rotary mud passage 156 are primary branch passages 157 which connect to the lower end of the collar 140 at the outside of the legs 145. Connected to the branch passages 157 are secondary branch passages 158 which connect to the lower end of the collar 140 inside the legs 145. The passages may be lined with suitable tubing indicated by the numeral 159. The parts of this form of the invention are assembled in substantially the same manner as in the first form of the invention. The insert 133 is attached in the socket 134 not by a separate retainer but by the engagement of the threads formed on the two parts. The body and cutter support are rotated relative to each other so that the insert is screwed into the socket 134. In this form of the invention I provide a bolt 160, shown in Figs. 17 and 19, for holding the cutter support members 131 together while the cutter support is being attached to the body 135. The bolt 160 has a head 161 which rests in a socket 162 formed in one of the cutter support members 131, a shaft 163 extended through openings 164 formed in the cutter support members 131, and a nut 165 which rests in a cavity 166 formed in one of the cutter support members 131. This bolt 160

may be left in the position shown in Fig. 19 when the bit is in use, or it may be removed therefrom after the cutter support members and the body have been secured together. The operation of this form of the invention is the same as the operation of the first form of the invention.

From the foregoing description it will be seen that my invention accomplishes numerous very important results. First, my invention provides a disk bit having inner disks located near the axis of rotation which are caused to rotate. This is a highly important feature since it makes it possible to provide the disks 77 in such a position as to prevent the formation of a core, which disks will 10 rotate so that their entire cutting edges will be utilized. By making spool cutters, as shown, integral, maximum strength is obtained which permits a disk bit to be made in a small size. In my invention I have a disk bit for a six-inch hole, which size has never 15 been attempted in the ordinary form of disk bit because it was impossible to obtain the required strength. The manner of assembling the cutter support members of the invention is important, since it permits an easy 20 assembly of the various parts, and when assembled these parts are rigidly attached together and cannot possibly become detached. Another feature of the invention is the extensibility of the cutter spools which permits the disk bit to drill a hole of larger size 25 than the casing through which the bit is passed.

I claim as my invention:

30 1. A rotary disk bit comprising: a spool cutter; a support for carrying said spool cutter, said support comprising a pair of substantially alike support members arranged to cooperatively extend around a hub of said 35 spool cutter; and means for securing said support members together.

2. A rotary disk bit comprising: a spool cutter; a support for carrying said spool cutter, said support comprising a pair of substantially alike support members arranged to cooperatively extend around a hub of said 40 spool cutter, said support having an insert; and a body having a socket into which said insert extends for securing said support members together.

3. A rotary disk bit comprising: a spool cutter; a support for carrying said spool cutter, said support comprising a pair of substantially alike support members arranged to cooperatively extend around a hub of said 45 spool cutter; means for securing said support members together; and means for locking said means and said support from relative rotation.

50 4. A rotary disk bit comprising: a spool cutter; a support for carrying said spool cutter, said support comprising a pair of substantially alike support members arranged to cooperatively extend around a hub of said 55 spool cutter, said support having an insert; a body having a socket into which said insert extends for securing said support members together; and means for locking said body and said support from relative rotation.

55 5. A disk bit comprising: a cutter; a sup-

port for carrying said cutter, said support consisting of a pair of substantially alike co-operating support members providing an insert; a body having a socket into which said insert is extended; and an axial retainer engaging said support members and said body for securing said support and said body together. 70

6. A combination as defined in claim 5 in which said retainer has a head located in a cavity of said support and is threadedly secured to said body. 75

7. A combination as defined in claim 5 in which said retainer has a head located in a cavity of said support and is threadedly secured to said body; and in combination with means for locking said retainer from rotation relative to said body. 80

8. A combination as defined in claim 1 in which said spool cutter may move axially outward from a retracted position into an extended position. 85

9. In a rotary disk bit, the combination of: a pair of spool cutters; a support member having legs in each of which is a bearing opening, said member being divided into sections, parting surfaces between said sections passing through said legs so as to intersect said openings, said legs being adapted to embrace the hubs of said cutters in said openings when said sections are assembled; and means for securing said sections together in assembled relation. 95

10. In a rotary disk bit, the combination of: a pair of spool cutters; a support member having legs in each of which is a bearing opening, said member being divided into sections, parting surfaces between said sections passing through said legs so as to intersect said openings, said legs being adapted to embrace the hubs of said cutters in said openings when said sections are assembled; an insert formed by portions of each of said sections; a body having a cavity adapted to receive said insert, said support member being thus held in assembly; and a member for retaining said insert in said cavity. 100

11. In a rotary disk bit, the combination of: a pair of spool cutters; a support member having legs in each of which is a bearing opening, said member being divided into sections, parting surfaces between said sections passing through said legs so as to intersect said openings, said legs being adapted to embrace the hubs of said cutters in said openings when said sections are assembled; an insert formed by portions of each of said sections; a body having a cavity adapted to receive said insert, said support member being thus held in assembly; a member disposed axially within said body for retaining said insert in said cavity; and means for preventing rotation of said support member relative to said body. 115

12. In a rotary disk bit, the combination of: a pair of spool cutters; a support member 120

having legs in each of which is a bearing opening, said member being divided into sections, parting surfaces between said sections passing through said legs so as to intersect said openings, said legs being adapted to embrace the hubs of said cutters in said openings when said sections are assembled; an insert formed by portions of each of said sections; a body having a cavity, and a threaded recess connecting with said cavity, said cavity being adapted to receive said insert, said support member being thus held in assembly; and a member adapted to be threadedly received in said recess for retaining said insert in said cavity.

13. In a rotary disk bit, the combination of: a pair of spool cutters; a support member having legs in each of which is a bearing opening, said member being divided into sections, parting surfaces between said sections passing through said legs so as to intersect said openings, said legs being adapted to embrace the hubs of said cutters in said openings when said sections are assembled; a body having a cavity into which the upper portion of said member is adapted to extend, said sections thereby being retained in assembly; and interlocking means formed upon said body and said support member which engage, when said body and member are moved together axially, to prevent relative rotation therebetween.

14. In a rotary disk bit, the combination of: a pair of spool cutters; a support member having legs in each of which is a bearing opening, said member being divided into sections, parting surfaces between said sections passing through said legs so as to intersect said openings, said legs being adapted to embrace the hubs of said cutters in said openings when said sections are assembled; a body having a cavity into which the upper portion of said member is adapted to extend, said sections thereby being retained in assembly; interlocking means formed upon said body and said support member which engage, when said body and member are moved together axially, to prevent relative rotation therebetween; and a retaining member interlocking with said support member and extending axially into said body to secure said support member and said body together.

15. A combination as in claim 12 in which a key for locking said retaining member against rotation is held in place between said body and a drill pipe joint to which it is attached.

16. A combination as in claim 14 in which a key for locking said retaining member against rotation is held in place between said body and a drill pipe joint to which it is attached.

In testimony whereof, I have hereunto set my hand at Los Angeles, California, this 10th day of December, 1926.

FREDERIC W. HILD.
